UNITED STATES PATENT OFFICE

121,416

DESIGN FOR A TEXTILE FABRIC

Abraham Katz, New York, N. Y.

Application May 15, 1940, Serial No. 92,375

Term of patent 3½ years

To all whom it may concern:

Be it known that I, Abraham Katz, a citizen of the United States and a resident of the city of New York, in the county of Kings and State of New York, have invented a new, original, and ornamental Design for a Textile Fabric, of which the following is a specification, reference being had to the accompanying drawing, forming a part thereof.

The figure is a plan view of a piece of the fabric showing my new design.

The design unit is enclosed between the dot and dash lines, which unit is repeated in regular succession as indicated.

I claim:

The ornamental design for a textile fabric, substantially as shown and described.

ABRAHAM KATZ.
